TENSION PULLEY

Per Gunnar Palmgren, Philadelphia, and Alfred Stewart Murray, Norristown, Pa., assignors to SKF Industries, Inc., Philadelphia, Pa., a corporation of Delaware

Application January 16, 1947, Serial No. 722,416

7 Claims. (Cl. 74—230.01)

1

This invention relates to improvements in tension pulleys for tape, band or belt drives in textile machines, and to the mounting of such pulleys in brackets attached to the machines.

A principal object of this invention is to provide a mounting for the pulley assembly that will render said assembly readily adaptable to brackets already in use for plain bearings and will permit quick installation in such brackets.

Another object is to provide a pulley having relatively low windage resistance.

Another object is to provide pulley parts that will not corrode in the relatively moist atmosphere of textile mills.

Still another object is to provide a pulley that will not, by sparking, set fire to the lint and dust prevalent in the air of textile mills.

A further object is to produce a pulley having excellent dynamic balance at low cost.

Other objects will appear from a consideration of the following description and of the attached drawings, wherein:

Fig. 1 is a front elevational and partial sectional view of pulley assembly made in accordance with the invention;

Fig. 2 is a side elevational view of the assembly; and

Figs. 3 and 4 are views in perspective of two different elements of the assembly.

Tension pulleys of the type involved conventionally hang in brackets attached to arms which swing around studs fixed to the frame of the textile machine. An overbalanced weight fastened to the arm causes the pulley to press against the tape, belt or band which drives one or more spindles of the machine, and thereby imparts a uniform tension throughout such belt or band. Such pulleys may turn at, say, two to five thousand revolutions per minute and thus require careful consideration with respect to several features in order that they may perform their functions with the least disturbance to the running of the tape and with the least consumption of power. First, the pulley should possess good dynamic balance so that it may run steadily and avoid any swinging of the arm which would cause whipping of the tape; second, it should operate with low friction to reduce power loss; third, it should not corrode in the moist atmosphere of the mills wherein such condition is often artificially produced; fourth, it should produce no static electrical charges that could result in a spark that might set fire to the fine lint and dust which pervades the air of such mills; and fifth, the pulley surface should remain free from

2

oil, grease or any film of lubricant straying from the bearing chamber.

We have achieved all of these and other desirable properties in the pulley by the organization of elements hereinafter described.

The invention consists of a pulley 1, which preferably is made of plastic material molded to precise dimensions in a completely finished state. The plastic material preferred for this pulley is one that will finish close to the dimensions required for proper fit of the anti-friction bearing upon which it is to be mounted, thus eliminating necessity for any finishing process such as grinding to bring it to size. The outer race of the said bearing must go into the pulley hub 2 with a press fit sufficient to hold it firmly without eliminating entirely the internal looseness of the bearing by reduction of the outer ring size. We have found that in general, plastic material requires five to ten times as much interference between the bore of the hub and the outside diameter of the bearing as does a cast iron or steel housing to produce internal fit conditions in the bearing in accordance with correct practice. The pulley therefore turns with the outer race 3 of the anti-friction bearing 4, shown in the drawings as a ball bearing, said race being fixed in the hub 2 integral with the sidewall 5. The bearing has a sealing plate 6 on the side opposite the sidewall 5 of the pulley, and the said plate and sidewall form in effect an enclosed chamber for holding grease which may be replenished through small holes 7 and 8, the hole 7 being in the pulley wall and the hole 8 in a cover plate 17 hereinafter described.

The inner race 9 of the bearing 4 is mounted on a shaft 10 with a press fit. The outboard ends of the shaft fit into round holes 11 in rectangular blocks 12 of wood, plastic, or any other suitable material. The blocks in turn rest loosely within rectangular boxes 13 each open on one side and on one end. Two steel springs 14 hold the blocks in place by pressing against one side, said springs being retained in position by notches 15. The blocks may be removed by swinging the springs out of the notches to one side as shown in dotted lines.

Support bracket 16, shown in the drawing but not described in detail is of the type conventionally used in textile machinery. Conventionally, also, the pulley is made of metal and is secured directly to the shaft 10. In such conventional installations the blocks 12 are formed of wood impregnated with oil and the shaft rests in the round holes with a slight clearance and operates

as a journal without further lubrication than that supplied by the oil soaked fibres of the wood. Because of the relatively high torque of this type of bearing and because its exposed surfaces set in motion a material volume of air, power consumption is relatively high. Though small in amount in each pulley, the windage loss becomes important when multiplied by the thousands of pulleys in operation throughout a given mill. The present invention minimizes these two frictional losses by replacing the plain high torque bearing with an anti-friction bearing properly lubricated and by employing plates 17, 17 which enclose all rotating surfaces of the bearing and pulley except the outer rim, thus reducing windage loss to a minimum. The plates 17, 17 are mounted on the shaft 10, as shown, and are normally stationary. It will be noted, however, that the plate which contains the hole 8 may be adjusted about the shaft so as to bring said hole into line with the hole 7, for the purpose of introducing lubricant as described, and so as to shift the hole 8 into an alternative position wherein it lies behind and, in effect, is sealed by a corner of the element 19 of a member 18 hereinafter described or, in the absence of such member, by a corner of the adjoining block 12.

It has been proposed to replace the relatively undesirable plain bearing, but heretofore such proposals have involved the elimination also of the aforesaid rectangular plain bearing blocks 12 and the employment of brackets lacking the rectangular boxes 13 which accommodated said blocks. In the present invention we have achieved ready application of the improved pulley assembly to brackets of the conventional form now in substantially universal use. This we have accomplished by the novel device of inserting the shaft into the holes of the blocks with a fit tight enough to fix it against rotation and by mounting the anti-friction bearing on that shaft. The blocks are fitted snugly to the pockets in order to preclude shaking of the pulley and preferably a rib 12a is provided on one face of the block, i. e., the outer face, which is engaged by the springs 14, to indicate the proper position in which the blocks should be inserted for closest fit.

We avoid corrosion on the moving parts by the use of plastic material for the pulley, and on the exposed stationary parts by making the plates of non-corrosive material such as aluminum, plastic or stainless steel. Corrosion tends to hinder smooth operation, to collect lint on the surfaces, hinder cleaning processes, and to wear out and thus shorten the life of the tape belt or band, and, if excessive, will destroy the usefulness of the pulley. Its effective elimination is therefore an important factor.

Danger of sparking due to accumulation of static is avoided by employing an L-shaped strip, 18, of metal shown in Fig. 4. One leg 19 of this angular strip is provided with an opening 20 for reception of the shaft 10 and, as shown in Fig. 2, this leg 19 is confined between the inner end of one of the blocks 12 and the proximate face of the adjoining plate 17 and in contact with the latter. The other leg 21 of the strip 18 lies between the block and the proximate face of the bracket 16 so that the pulley 1 is in effect grounded to the bracket.

We have achieved good dynamic balance without finishing processes, by employing a plastic, such as flock-filled phenolic plastic, that molds to size controllable to a dimensional accuracy of about .001 of an inch per inch of diameter. The

saving of all finish processing reduces cost to a minimum figure, considerably below the cost of corresponding parts made of metal.

While we prefer the above described construction because of its low cost and efficiency, certain changes may be made within the scope of the invention, such, for example, as grinding a groove in the shaft to accommodate the balls of the bearing, thereby eliminating requirement of a separate inner race.

We claim:

1. In a pulley assembly, a bracket having bifurcations affording therebetween a space for said pulley and each containing a lateral recess open 15 at its inner end to said space, a relatively fixed shaft intersecting said space and extending at the ends into the respective recesses, stationary means confined in said recesses and anchoring the said ends of the shaft in the bracket, a pulley 20 mounted for rotation about the shaft within said space, and anti-friction bearing means interposed between the pulley and the shaft.

2. A pulley assembly according to claim 1 wherein the said stationary means are composed 25 of nonmetallic material, and wherein further means is provided for grounding the pulley to the bracket.

3. A pulley assembly according to claim 1 wherein the said stationary means are composed 30 of nonmetallic material, and wherein further a metallic strip is confined by the stationary means in one of said recesses in contact with the shaft and the bracket to form an electrically conductive path therebetween.

35 4. In a pulley assembly, a relatively fixed shaft, a pulley mounted for rotation about the shaft, said pulley having a radial flange extending in proximity to the shaft and an axial recess terminating at its inner end in said flange, an anti-friction bearing housed in said recess and supporting the pulley on the shaft, a disc at each 40 axial side of the pulley secured to the shaft and extending outwardly into proximity to the periphery of the pulley to form stationary face plates 45 for the latter, and aligned perforations in the said radial flange and the adjoining face plate to afford access to the bearing for introduction of a lubricant.

5. In a pulley assembly, a stationary shaft, a 50 pulley journaled on the shaft, an anti-friction bearing interposed between the pulley and the shaft, a plate mounted on the shaft at one side of and in proximity to the pulley and forming in effect a facing for the latter, said plate being 55 normally stationary and being adjustable about the shaft, a stationary member adjoining the outer face of said plate, and an aperture in the plate normally lying behind and being closed by said stationary member, said aperture being movable by rotative adjustment of the plate to an exposed position clear of said member to afford access therethrough to the said bearing for application to the latter of a lubricating medium.

6. A pulley assembly according to claim 5 65 wherein the bearing is located in a transverse recess in the pulley, and wherein further the portion of the pulley which forms the bottom wall of the recess is provided with an aperture arranged for registration with the aperture in the face 70 plate when the latter aperture is in the exposed and operative position.

7. In a pulley assembly, a relatively fixed shaft, a pulley mounted for rotation about the shaft, said pulley having an axial recess and a wall 75 closing one side of said recess, a disc secured to

the shaft and confronting the open side of the recess, a second disc secured to the shaft confronting the outer face of the wall at the closed side of the recess and enclosing a narrow space between itself and said wall so as to restrict to a small amount the volume of air frictionally moved by operation of the pulley, both of said discs extending outwardly into proximity to the periphery of the pulley so as to form stationary facing plates for the latter.
